ABSTRACT OF THE DISCLOSURE

Apparatus is provided by which opposing faces of a split workpiece may be lapped readily to a face-to-face fit. The workpiece is held by the apparatus in a fixed position with a lapping blade inserted between the opposing faces of the split and reciprocated. The lapping blade is shaped so that upon insertion it contacts the respective faces of the split in a relation that corresponds to the face-to-face fit desired; and the blade is arranged for reciprocation so that it is always free to find an aligned position between the opposing faces being lapped, and so that it is always pulled during the reciprocation.

BACKGROUND OF THE INVENTION

A problem has persisted over the years with the excessive hand labor required in forming the split rings used to seal the breechblock juncture in artillery pieces. These split rings are used to form a gastight seal between the firing chamber and the breechblock, and they are split so that they will expand to a gastight seating under firing pressure. The splits are formed diagonally in the rings to allow for this expansion while providing relatively extended faces at the split for opposing contact, and it is necessary that these opposing faces of the split have a fine face-to-face fit in order to maintain the rings gastight at this point.

Fitting of the split faces is commonly done by hand lapping which is not only slow and tedious but also requires a degree of skill that is difficult to recruit and maintain satisfied in the face of the exacting demands of this operation. U.S. Pat. No. 2,401,279 contains a prior art proposal for mechanizing the lapping operation, but this proposal was apparently unsuccessful for hand lapping still persists as the practice in common use.

It appears likely that failure of the above-noted prior art proposal to replace the hand lapping procedure was due principally to a failure to see the necessity for lapping the respective split faces mechanically in a relation that corresponds to the face-to-face fit required, although other aspects of the apparatus suggested by this previous proposal have serious practical disadvantages as well.

The present invention provides means for lapping the split rings that is now being used to eliminate the hand lapping entirely.

SUMMARY OF THE INVENTION

The lapping means provided by the present invention comprises a fixed means for supporting the split rings with the split therein positioned for lapping; a lapping blade shaped for inserting between the opposing faces of the split so that the respective split faces are contacted by the blade in a relation that corresponds to the relation that must be assumed by the faces when face-to-face; a holder for the lapping blade; and a reciprocably mounted carrier for the blade holder; the carrier and holder being respectively arranged so that the latter is always free when carried by the former to allow the held lapping blade to find an aligned position between the opposing split faces being lapped, and so that the latter and the

2

held lapping blade are always pulled upon reciprocation of the former.

This apparatus arrangement is described further below in terms of an embodiment adapted particularly for lapping the previously mentioned split rings, although it should be recognized as being generally applicable for lapping split workpieces of any comparable sort.

DESCRIPTION OF THE DRAWINGS

- 10 FIG. 1 is a side elevation of means embodying the present invention for lapping the opposing split faces of the previously mentioned split rings;
15 FIG. 2 is a plan view corresponding to FIG. 1;
15 FIG. 3 is a right-side view of the work support superstructure as seen from the position 3—3 in FIG. 2;
20 FIG. 4 is a sectional detail of the lapping blade and blade holder taken at the line 4—4 in FIG. 1;
20 FIG. 5 is a plan view of a split ring such as is lapped by the means of the present invention;
25 FIG. 6 is a sectional detail taken at the line 6—6 in FIG. 5; and
FIG. 7 is a bottom side view corresponding to FIG. 5.

DESCRIPTION OF THE PREFERRED EMBODIMENT

25 In the illustrated embodiment a base plate is designated by the reference numeral 10 on which the several apparatus elements are positioned.

The work support, indicated generally by the reference numeral 12, is held on the base plate 10 by clamp pieces 14 bolted in place to grip the support 12 at a fixed disposition, while allowing it to be removed readily for replacement by a counterpart whenever a different size of split ring R must be handled.

30 35 The clamp pieces 14 grip edge portion 16 of a work support base structure 18 that rises to provide an elevated table surface at 20 on which a superstructure 22 is bolted at an angled disposition to hold the split ring R for lapping. The split ring R is held at an upright front plate portion 24 of the superstructure 22 that is braced by gussets 26 at its back face and has its front face fitted with a jig piece 28 and with top and side clamps 30 and 32. The jig piece 28 has curved end portions 28' and 28" that fit the inner diameter of the split ring R for locating purposes, and it is arranged at the right side of the front plate 24, opposite the side clamp 32, so that a split ring R positioned around its end portions 28' and 28" will extend within the reach of both the top and side clamps 30 and 32.

40 45 50 A split ring R is installed on the front plate 24 for lapping, as seen in FIG. 1, with the square edge of its split S disposed vertically, or substantially so, and downwardly opposite the top clamp 30. Both of the top and side clamps 30 and 32 are fitted with clamp screws 30' and 32' operable by hand to tighten them on the installed split ring R, and the side clamp 32 has an upwardly extending arm portion 32" bolted at its extending end to the front plate 24 to maintain this clamp in position for such tightening.

55 60 65 The work support superstructure 22 additionally carries a presser bar 34 at the right edge of the front plate 24, which is pivoted at its upper end on a stud 36 and is backed at its lower end by a cam roll 38 that is carried at an eccentric axis 40 and provided with an operating lever 42 (as seen best in FIG. 3). Movement of this operating lever 42 to the right from its upstanding FIG. 3 position causes the cam roll to bias the pressure bar 34 outwardly about its pivot stud 36 and thereby press the overlying portion of the split ring R, adjacent the jig piece 28, outwardly as well to force the split S open for the lapping purpose that will be noted presently. Before passing from the work support superstructure 22, how-

ever, it should also be noted that a further jig bracket 44 is bolted in place at 46 behind the front plate 24 and extends around the presser bar 34 to carry an adjustable positioning screw 48 for use in holding the split ring R seated on the jig piece 28 during installation.

Use of the presser bar 34 to force the split S open in the above-noted manner allows insertion of a lapping blade 50 between the opposing faces of the split in preparation for the lapping operation. The lapping blade 50 is formed (see FIG. 4) by a rigid base element 52 having an abrasive sheet 54 folded thereover and clamped together with the base element 52 on a holder 56 by a clamping bar 58 bolted to the holder 56.

The base element 52 of the lapping blade 50 is specially shaped with a tapered cross section so that the lapping blade portion extending from the holder 56 between the opposing faces of the ring split S will establish lapping contact with these faces in a relation that corresponds to the parallel face-to-face relation which the faces must assume when the lapping blade 50 is removed. The particular taper employed will depend primarily on the size of split ring R being handled, and different base elements 52 must be employed for each ring size, but the proper taper can be empirically determined quite readily in each instance to lap the split faces with exceptional accuracy.

Once the lapping blade 50 has been inserted between the opposing faces of the split S, the operating lever 42 is released to remove the opening bias imposed through the presser bar 34 and allow closing of the split faces on the lapping blade 50. When this happens the split faces will bear oppositely on the lapping blade 50 to urge it toward an aligned disposition, and the blade holder 56 is arranged to allow this alignment to take place. For this purpose, the blade holder 56 is fitted with hanger portions 60 at each end from which trunnions 62 extend to rest freely in horizontal slots 64 of spaced supporting arm portions 66 rising from a carrier 68. By this arrangement, the holder 56 and held lapping blade 50 are always maintained free to swing about the trunnions 62 to find the vertical alignment urged by the opposing faces of the split S, and to assume the dictated longitudinal alignment as well through responsive lateral shifting of the studs 62 in the slots 64.

The carrier 68 is reciprocably mounted on a crosshead 70 supported by a pillow block 72 bolted to the base plate 10. Mounting of the carrier 68 on the crosshead 70 is provided for at a stub rod 74 extending from a post member 76 on the carrier 68 to enter a bore 78 in the adjacent end of the crosshead 70. The stub rod 74 is shouldered for penetration of the crosshead bore 78 to a fixed extent, and is circumferentially grooved toward its extending end for engagement by a set screw 80 installed in the crosshead 70.

The other end of the crosshead 70 has a connecting rod 82 pivoted thereto which extends from a crank plate 84 carried on a shaft 86 that is mounted in further pillow blocks 88 on the base plate 10 for driving from a motor 90 also mounted on the base plate 10. Operation of the motor 90 consequently results in ultimate reciprocation of the lapping blade 50 to cause lapping of the opposing split faces between which it is disposed, and it should be noted in particular that the lapping blade 50 is always pulled during this reciprocation by reason of the fitting of each blade holder trunnion 62 with a washer 92 and backing pin 94 to provide shoulder means in shortly spaced relation beyond the spaced supporting arm portions 66 of the carrier 68, so that upon each reversal of the reciprocating movement the carrier 68 engages the blade holder 56 at the end disposed forwardly in the direction of reciprocation to pull the lapping blade 50 and thereby eliminate any tendency for it to buckle during any phase of the lapping operation.

The foregoing embodiment of the lapping means of the present invention is employed in the course of form-

ing a split ring R as follows. After rough machining a solid ring to serve as a blank for the split ring R, this blank is heat treated and then specially reheated for a local twisting to introduce a "kink" that stresses the blank to impose a closing, spring-like, bias at the split S after it is cut, as noted in the previously mentioned U.S. Pat. No. 2,401,279. The diagonal split S is then cut in the blank with an abrasive saw at a position located in 180° relation to the "kink," so that the imposed bias is applied in a balanced manner to urge the opposing faces of the cut split together.

At this point, a first lapping operation is performed to give the split faces an initial fit. A lapping blade 50 of selected taper for the size of ring R being handled is employed, and the "kink" bias maintains both faces of the split in contact with the blade 50 as the operation proceeds. At this first lapping operation, however, the saw cut will have left the opposing split faces somewhat out of parallel in their closed position, and the abrasive sheet 54 employed in the lapping blade 50 at this stage is therefore a relatively coarse emery cloth capable of working the split faces roughly into parallel relation with a coarser finish than is ultimately required.

When an initial fit has thus been obtained at the split S, it is soldered so as to be held as if it were solid while the ring R is given a semi-finish machining all over, after which the solder is removed by heating and a second lapping operation is employed, this time with a relatively fine emery cloth to begin the finish lapping of the split faces. This second lap is again followed by soldering of the split S and a further semi-finish machining of the ring R all over to work it closer to the final dimensions that must be reached quite precisely.

Then the solder is removed from the split S again by heating and it is subjected to a third and final lapping operation to finish the face-to-face fit of the split faces, before a finish machining and grinding of the ring R all over, and a deburring and chrome plating, all with the split S again soldered fast. The finished ring R is then subjected to an inspection while held solid by the solder, and to a final inspection after removing the solder from the split S and cleaning it.

When the several lapping steps involved in the foregoing procedure are performed by hand at least 15 minutes is required for the first, 30 minutes for the second step, and an hour for the third, even when the requisite skill is steadily applied. The practical fact of the matter, however, is that it is exceedingly difficult to keep the requisite hand skill available for these lapping steps so that the supervision necessary to maintain the hand lapping in reasonable step with the procedure as a whole is unduly burdensome even when successful.

In contrast, the lapping means of the present invention allows the first lapping step to be performed readily in 3 minutes, and the second and third steps in about 4 minutes, with regularly consistent results. When a batch of split rings R of a given size is to be processed, the proper taper for the lapping blade 50 is selected at each lapping step by first trying the blade taper that prior experience has indicated as likely to be suitable. A lapped ring R is then inspected by applying a bluing coat to one face of the split S and observing the impression obtained on the other face. If the impression obtained is not satisfactory, a blade 50 of different taper is substituted and the ring R is lapped again and inspected until the proper relation of the split faces during lapping results.

While slight differences in physical characteristics or treatment of the rings R from batch to batch will often require adjustment of the lapping blade taper to suit each batch, not more than one adjustment is ordinarily required after a little experience has been gained as to the likely taper needed for a given size ring. For the size range of split rings R normally employed in artillery pieces, we have used blades 50 ranging in taper from .003 inch/inch to .0133 inch/inch in steps usually of .001 inch/inch.

And as a greater taper is needed as the diameter of the ring becomes smaller, it soon becomes possible to select the proper taper for a given ring size quite closely.

In providing lapping blades 50 of different taper, it is preferable to maintain the tip of the base element 52 on which the taper is formed at a constant width so that the superimposed abrasive sheet will fold over all of the base elements in comparable fashion. We have used a tip width dimension of .031" for our base elements 52, which are formed from flat ground steel stock $\frac{1}{16}$ " x 2" x 9".

The abrasive sheet 54 is suitably "Metallite" emery cloth as supplied by the Norton Company. This emery cloth may be obtained in 50' rolls of 4" strip so that pieces are cut readily to fit the above-noted base element 52, and is formed with aluminum oxide grit installed on a light-weight cloth backing by a resin bond that stands up well under pressure. For the first lapping step we use a grade designated at 100X that bears a grit yielding a finish in the order of 60 to 75 microinches, while the 240X grade is employed for the second and third lapping steps to provide a grit yielding a finish in the 15 to 20 microinch range. A new piece of emery cloth is installed for lapping each ring R, which may be readily done with lapping blade arrangement employed in our lapping means, and a timing device (not shown) is preferably used to control the lapping period for each ring R.

Standard specifications for split rings R of the sort being considered here require a minimum 80% contact area between the faces of the split S. With the lapping means of the present invention it is possible to produce a 95% contact area at the second and third lapping steps with consistent ease.

The present invention has been described in detail above for purposes of illustration only and is not intended to be limited by this description or otherwise to exclude any variation or equivalent arrangement that would be apparent from, or reasonably suggested by, the foregoing disclosure to the skill of the art.

What is claimed is:

1. Apparatus for lapping opposing faces of a split workpiece to a face-to-face fit comprising fixed means for supporting said workpiece with the split thereof positioned for lapping the opposing faces thereat, a lapping blade shaped for insertion between said opposing faces in a relation to

the respective faces that corresponds to the face-to-face fit desired, a holder for said lapping blade, and a reciprocably mounted carrier for said holder, said carrier and holder being respectively arranged so that the latter is always free when carried by the former to allow the held lapping blade to find an aligned position between said opposing workpiece faces and so that the latter and the held lapping blade are always pulled upon reciprocation of the former.

10 2. Apparatus as defined in claim 1 and further characterized in that said fixed supporting means is equipped with selectively operable biasing means for forcing said opposing workpiece portions apart to allow insertion of said lapping blade therebetween.

15 3. Apparatus as defined in claim 1 and further characterized in that said workpiece is ring-shaped, in that the split is diagonally formed in said workpiece, and in that said lapping blade has a transverse cross section that is tapered at the degree necessary for lapping the respective faces of said split in a relation that will render said faces parallel when said lapping blade is removed.

20 4. Apparatus as defined in claim 1 and further characterized in that said holder is formed for releasably clamping said lapping blade, and in that said lapping blade is formed by a rigid base element and an abrasive sheet folded thereover for clamping together with said base element in said holder.

25 5. Apparatus as defined in claim 1 and further characterized in that said carrier has spaced supporting arm portions that are horizontally slotted, and in that said holder has trunnions extending at each end to rest freely in said supporting arm slots and extend therethrough with shoulder means fitted to said trunnions in shortly spaced relation beyond said supporting arm portions.
